UNITED STATES PATENT OFFICE.

JOSEPH J. COX, OF LAWRENCE, KANSAS, ASSIGNOR OF TWO-THIRDS TO
CONSTANT J. CARTWRIGHT AND CLARENCE Z. KELSO, BOTH OF SAME
PLACE.

FEED-COOKING APPARATUS.

SPECIFICATION forming part of Letters Patent No. 315,389, dated April 7, 1885.

Application filed June 28, 1884. (No model.)

To all whom it may concern:

Be it known that I, JOSEPH J. Cox, of Lawrence, in the county of Douglas and State of Kansas, have invented a new and useful Improvement in Feed-Cooking Apparatus, of which the following is a full, clear, and exact description, reference being had to the annexed drawings, forming part of this specification.

10. This invention relates to apparatus for steaming and boiling feed for animals; and it consists of the construction hereinafter described and claimed.

15. In the drawings, Figure 1 is a longitudinal section, and Fig. 2 a cross-section, of my invention.

A indicates a boiler supported on a double furnace, B C, the compartments of which are separated from each other by the partition D. 20. The flues E F extend toward the ends of the boiler, and are made broad enough to expose the entire bottom of the boiler to the heat of the smoke, which escapes through pipes G at the ends of the apparatus. The boiler is made 25. with double walls H, to form an air-space, I, to impede the radiation of heat. Instead of the air-space I, non-conducting material may be secured to the outer surface of the sides of the boiler.

30. The boiler is formed with an offset, J, on the inner side, forming a support for the grating K, which divides the boiler into two compartments, L M, the upper compartment being used for steaming feed—such as corn in the ear—while the lower compartment is used for boiling shelled grain. The boiler is covered by a concavo-convex lid, N, which assists in confining the steam.

O indicates a folding platform, on which the attendant stands to place him in convenient reach of the interior of the boiler. P Q are the doors of the furnace, and R an extra feed-door for coal. S T are dampers, by which the furnace may be closed tight to prevent danger from fire when required.

45. The furnaces may be constructed for either coal or wood, as desired.

With the above-described construction, by locating the furnace or furnaces under the center of the boiler and extending the flues to the ends of the same, the heat is fully utilized and distributed throughout the apparatus, causing the feed to be evenly cooked. This construction also admits of the use of a comparatively small furnace, requiring comparatively little fuel.

55. What I claim is—

1. The feed-cooking apparatus having the long boiler combined with a furnace having separate chambers located under the center 65 of the boiler, and separate flues for said chambers extending to opposite ends of the boiler, substantially as shown and described.

2. The combination, with the boiler A, of the separate furnaces B C, arranged under the center of the length of the boiler, and provided with the flues E F, respectively, extending to the ends of the boiler, and with the dampers S T, substantially as herein shown and described.

JOSEPH J. COX.
